UNITED STATES PATENT OFFICE.

WEBSTER GILL, OF CAMDEN, NEW JERSEY.

CONDENSER FOR CARDING-MACHINES.

SPECIFICATION forming part of Letters Patent No. 357,478, dated February 8, 1887.

Application filed April 24, 1886. Serial No. 200,046. (No model.)

To all whom it may concern:

Be it known that I, WEBSTER GILL, a citizen of the United States, residing at Camden, in the county of Camden and State of New Jersey, have invented certain new and useful Improvements in Condensers for Carding-Machines; and I do hereby declare the following to be a full, clear, and exact description of the invention, reference being had to the accompanying drawings, which form part of this specification, in which—

Figure 1 is a plan view of a condenser with my improvements applied thereto. Fig. 2 is a side elevation of the same.
15 My invention has for its object to provide means whereby the sliver, as it comes from the doffer of a carding-machine, may be twisted and drawn before it reaches the condenser-aprons, for the purpose of reducing and rendering it more compact before being acted upon by the rubbing-aprons.

Carders have generally recognized the difficulty of drawing wool with the devices now in use, which consist of a train of rolls of increasing speed, owing to the fact that the sliver, if not twisted, will not bear much draft without breaking, and have also appreciated the fact that it would be desirable to give the sliver considerable draft, in order to bring it into better condition for spinning on the mule. It is a fact that if a sliver of wool be subjected to much draft it will break or part, and that if it be twisted while being drawn the twist will go to the weakest part of the sliver and strengthen 30 the same, any breaking that may occur thereafter taking place in the untwisted portion. Where a partial separation of sliver takes place it results in unevenness in the yarn when spun.

I have discovered that by the means I provide a twist may be imparted to the sliver between the doffer of the carding-machine and the rubbing-aprons of the condenser, whereby such sliver may be drawn, the twisting enabling the draft to be effected without destroying 45 the uniformity of the slubbing, and the draft rendering such slubbing more compact and in better form to be acted upon by the rubbing-aprons than it would otherwise be.

My invention consists, essentially, in the provision of two cross belts or aprons between the doffer-roll of the carding-machine and the

condenser rubbing-aprons, and arranged obliquely or diagonally to the shafts of both the doffer-roll and the rubbing-aprons, being so located that they receive the sliver from the 55 carding-machine and deliver it to the rubbing-aprons, imparting a twist to such sliver and producing a draft upon the latter in its passage.

Referring to the accompanying drawings, A 60 represents a frame, which may be the frame of the condenser, on which are supported rubbing-aprons B B, mounted on rolls C C, whose axes or spindles e e have a longitudinal reciprocation imparted to them, while they rotate 65 in the usual manner of rubbing-aprons of condensers by means of eccentrics E E', or by other equivalent mechanism.

F represents the doffer-roll, and F' an additional roll, which two combined constitute ten- 70 sion-rollers, and which may be on the discharging end of the carding-machine or upon the frame A.

G and H represent two aprons, of the same material and construction as are usually employed for the rubbing-aprons of condensers for carding-machines, and which are mounted upon rolls g g and h h, the latter having bearings in uprights or standards g' h' on the frame A. These aprons and their rolls are located 75 between the rubbing-aprons B B and the tension-rolls F F', and said aprons G and H are arranged obliquely or diagonally with reference to the axes or spindles of the rubbing-apron rolls and doffer or tension rolls. 80

Any suitable form of gearing or belting may be employed to communicate motion to the aprons G and H, which I designate as "twist-aprons." In the drawings I have illustrated their roller-shafts as having pulleys I and K, 85 which receive belts i and k, passing over pulleys l' l on a cross-shaft, L, having bearings in the frame A. These belts revolve in the direction of the arrows x y, and in operation run at such speed that they will produce draft 90 on the sliver delivered to them by the tension-rolls F F', or from the doffer of the carding-machine. 95

The various belts and pulleys shown in the drawings (which are not of the essence of my invention) are designated as follows: A belt, f, running on pulley l' on shaft L, and on a

pulley, f' , on shaft of roller F' , communicates motion to said roller. A belt, m , running from large pulley M on shaft L around a pulley, P , on the shaft of the eccentrics $E E'$, 5 communicates rotary motion to said shaft, and a crossed belt, N , running over a pulley, ℓ , on shaft L , thence around a pulley, n , on one of the shafts of the upper rubbing-apron B , thence around an idler-pulley (not shown in 10 drawings) to a pulley, n' , on one of the shafts of the lower apron B , communicates rotary motion to the rolls $C C'$, and causes said aprons to travel.

The sliver, as it comes from the carding-machine, passes between the rollers $F F'$, and thence between the belt G and belt H , said belts imparting a twist to and imposing draft upon such sliver, so that the latter is both twisted and drawn as it comes from the doffer before delivery to the rubbing-aprons $B B'$. The twist given to the sliver is a peculiar one in this, that it is made as said sliver enters to the twist-aprons and becomes undone as it passes therefrom. The effect of the twist 15 is to permit draft to be imposed on the sliver without injurious results, and the effect of the draft is to make the sliver more compact, so that it is delivered to the condensing rollers or aprons in the form of a roll or slubbing already 20 partially condensed, the twist-aprons not only twisting the sliver, but also drawing it, as said aprons move faster than the tension-rolls $F F'$.

I have illustrated the condenser as having 25 aprons on the upper and lower rolls; but, as the rubbing-aprons are not my invention, one apron acting against rolls may be used; or, if desirable, the rubbing-aprons may be dispensed with and the rubbing be effected by 30 means of upper and lower rolls.

If desired, the twist-aprons may be supported upon a separate frame from frame A , and the tension-rollers, which are illustrated 35 in the drawings as being upon said frame A , 40 may be supported upon the frame of the card-

ing-machine, said tension-rollers consisting of the usual doffer-roller and an additional roller, forming a pair of rollers whose surfaces are so close as to cause them to bind upon the sliver in its passing through them.

What I claim as my invention is—

1. The combination, with rubbing aprons or rolls, for a carding-machine, of twist-aprons G and H , which cross each other and are arranged diagonally with respect to the axes or spindles of the rubbing rolls or aprons, substantially as shown and described. 55

2. The combination, with the doffer-roll of a carding-machine and rubbing aprons or rolls therefor, of twist-aprons located between the doffer-roll and the rubbing aprons or rolls, said twist-aprons crossing each other, and being arranged diagonally with respect to the axes of the doffer-roll and rubbing-rolls, substantially as shown and described. 60

3. The combination, with rubbing aprons or rolls and the doffer and tension rolls of a carding-machine, of two aprons mounted on rollers and provided with mechanism whereby said aprons are caused to run faster than the doffer and tension rolls, said aprons crossing each other, and being arranged diagonally with reference to the doffer-roll and rubbing-apron axes or spindles, whereby the sliver in its passage from the doffer-roll to the rubbing-aprons is twisted and drawn, substantially as shown and described. 65

4. The combination, with tension-rollers $F F'$ and rubbing aprons or rolls, of intermediate twist-aprons crossing each other and diagonally arranged, substantially as shown and described. 70

In testimony that I claim the foregoing I have hereunto set my hand this 19th day of April, 1886.

WEBSTER GILL.
